W. O'NEEL

BOTTLE REFRIGERATOR

Filed March 7, 1923

INVENTOR
Walter O'Neil,
BY
Arthur M. Hood,
ATTORNEY

UNITED STATES PATENT OFFICE.

WALTER O'NEEL, OF SHELBYVILLE, INDIANA.

BOTTLE REFRIGERATOR.

Application filed March 7, 1923. Serial No. 623,313.

To all whom it may concern:

Be it known that I, WALTER O'NEEL, a citizen of the United States, residing at Shelbyville, in the county of Shelby and State of Indiana, have invented a new and useful Bottle Refrigerator, of which the following is a specification.

My invention relates to improvement in refrigerators, and particularly to refrigerators for cooling bottles containing beverages and the like.

One of the objects of my invention is to provide a beverage bottle refrigerator which may be so constructed as to permit ready removal of the cooled bottles therefrom without opening the ice chamber of the refrigerator to the atmosphere each time a bottle is removed from the refrigerator.

Another object of my invention is to provide a beverage bottle refrigerator from which the bottles may be removed without the necessity of the dispenser feeling around through a large mass of ice to find a bottle of the particular beverage desired.

For the purpose of disclosing my invention, I have illustrated one embodiment thereof in the accompanying drawings, in which,

Fig. 1 is a perspective view of a refrigerator embodying my invention;

Fig. 2 is a longitudinal sectional view of the refrigerator shown in Fig. 1;

Fig. 3 is a sectional view taken on the line 3—3 of Fig. 2;

Fig. 4 is a detail perspective of the bottle removing clip, and

Fig. 5 is a longitudinal sectional view of a modified form of my refrigerator.

In the structure illustrated, the container 1 is provided with a bottle chamber 2 having a rear cover 3 and a front cover 4 provided with suitable openings 5 through which the bottles may be inserted in the chamber and through which the bottles may be removed from the chamber. These openings are closely adjacent the two ends of the chamber and the openings are maintained closed by suitable closure caps 6.

Above the bottle chamber there is provided an ice chamber 7, the open bottom of which terminates in the bottle chamber, the front and rear walls of the ice chamber being provided with downwardly extending lips 8 and 9 which form, in effect, a continuation of the front and rear walls of the ice chamber and project below the under side of the

top walls 3 and 4, of the bottle container. Arranged within the ice chamber 7 is an ice basket 10 which may be supported therein in any suitable manner, as by having the top side rods 11 embedded at each end in the side walls of the container. Access may be had to the ice chamber 7 through a top opening 12 which is arranged to be sealed by a cap 13 screw-threaded into the walls of the opening 12 so that, when the cap is in position, the top of the ice chamber is sealed to the atmosphere. The lip 9 of the front wall of the ice chamber terminates at a point just sufficiently above the bottom of the bottle chamber to permit the tallest bottle stored in the bottle chamber to clear the same. Vent pipes 14 and 15 are preferably embedded in the walls of the ice chamber and open into the chamber at a point approximating the top of the ice basket and into the bottle chamber at a point above the bottom of the lips 8 and 9, but slightly below the under side of the top or closure portions 3 and 4.

The bottom 16 of the bottle chamber is preferably inclined toward the front, or delivery end of the chamber and the bottle chamber is provided with suitable bottle guides 17 preferably in the form of rods having their front and rear ends embedded in the front and rear walls of the chamber. The guide-ways for the bottles formed by these guides 17 are beneath and coincide with the openings 5 so that when the bottles are deposited in the receiving opening they will drop into a guide-way and, due to the inclined bottom 16, the bottles will be fed forward by gravity to a point beneath the openings at the front end of the refrigerator. The bottles are adapted to rest on raised platforms 18 on the bottom 16 so that their bottoms will be clear of the bottom of the container. In order to assist gravity in feeding the bottles forward, each guide-way is provided with a weighted roller 19 adapted to be placed behind the last of the row of bottles, and this roller is preferably connected to the rear wall of the bottle chamber by a chain or cable 20 so that the roller may be retracted.

For lifting the bottles out of the bottle chamber, I preferably provide a bottle clip 21 at the front end of each guide-way, which is provided with a fork 22 arranged to engage the neck of the bottle beneath the top bead thereof and the handle 23 of the

clip is arranged to be supported at a point near the delivery opening.

In use, the bottle chamber is preferably filled with water until its level rises to a point where it will seal the ice chamber. The ice basket is filled with ice and as the ice melts the water level in the ice chamber will gradually rise. However, the ice chamber is always sealed to the atmosphere so that the ice in the ice chamber will tend to keep for a comparatively long period. Due to the fact that the lip 9 projects below the end of the vent pipe 14, the water level may be maintained in what may be termed the delivery well of the bottle chamber, well above the top of the bottle so that all the bottles in the bottle chamber will be well submerged in the liquid. Due to the fact that heated liquid tends to rise, as the cooling liquid becomes slightly heated, when the closure members 6 are opened to extract a bottle, there is a thermo-syphon circulating effect caused in the bottle and ice chamber so that the heated liquid will tend to rise to come in contact with the ice and be immediately chilled, and the bottles will be submerged in the coolest liquid at all times.

I claim as my invention:

1. A bottle refrigerator, having a bottle chamber provided with a delivery opening therein and adapted to contain cooling liquid and an air tight ice chamber adjacent said bottle chamber and communicating therewith, said ice chamber being adapted to be closed to the atmosphere by a supply of liquid in said bottle chamber.

2. A bottle refrigerator, including a bottle chamber arranged to contain cooling liquid, and having a delivery opening therein, an ice chamber communicating with said

bottle chamber and adapted to receive liquid from said bottle chamber, said ice chamber being closed to the atmosphere by the liquid in said bottle chamber, and means for feeding the bottles in said bottle chamber toward the delivery opening therein.

3. A bottle refrigerator, having a bottle chamber provided with a delivery opening, and an ice chamber having its bottom opening into said bottle chamber, said chambers being arranged to contain a liquid-cooling medium which seals the bottom of the ice chamber to the atmosphere.

4. A bottle refrigerator including a bottle chamber having an inclined bottom for receiving the bottles and provided with a top opening at the deepest end of said chamber, and an ice chamber above said bottle chamber and having its bottom opening into said bottle chamber and adapted to be sealed to the atmosphere by the cool liquid contained in said bottle chamber, and an ice receptacle arranged in said ice chamber.

5. A bottle refrigerator, including a bottle chamber having a delivery opening therein and having adjacent said opening a bottle well, means for delivering a bottle into said well when a bottle has been removed therefrom, and an ice chamber arranged above said bottle chamber and having its bottom opening into the bottle chamber, said ice chamber and bottle chamber arranged to receive a cooling liquid and said ice chamber being sealed to the atmosphere by said cooling liquid.

In witness whereof, I, WALTER O'NEEL, have hereunto set my hand at Indianapolis, Indiana, this 5th day of March, A. D. one thousand nine hundred and twenty-three.

WALTER O'NEEL.
